MULTIJET TORCH CONSTRUCTION

Howard G. Hughey, Bloomfield, N. J., assignor to
Air Reduction Company, Incorporated, New
York, N. Y., a corporation of New York

Application February 18, 1939, Serial No. 257,070

6 Claims. (Cl. 158—27.4)

This invention relates to improvements in the construction of oxy-fuel gas torches which have a number of orifices supplied with gas from a common distributing chamber.

In order to distribute the gas to the different orifices evenly and thus obtain flames of substantially the same size and intensity from all of the jet passages, it has been proposed that the distributing chamber be made with a cross-section that decreases as it extends away from the gas inlet passage.

The gas for all of the flames passes along the inlet end of the distributing chamber. Some of the gas flows from the chamber through each of the jet passages, however, so that the volume of gas flowing in the distributing chamber just ahead of the last passage is only a fraction of that which flows through the inlet end of the chamber.

In a ten-flame tip, for example, the end portion of the distributing chamber that supplies gas to the last jet passage only, has a gas flow equal to only ten per cent. of the gas flow in the other end of the distributing passage. By making the cross-section of the distributing chamber between successive jet passages substantially proportional to the volume of gas flowing in that part of the chamber, the velocity of the gas flow in the chamber past each of the jet passages is equalized, with the result that substantially the same static pressure head is obtained at each passage and the gas discharged from each orifice is the same.

In its broadest aspects this invention has for its object the providing of an improved multiple-flame torch, but a more specific object of the invention is to provide a simpler and more economical torch construction by which the desired change in cross-section of the gas distributing chamber is obtained.

In accordance with one feature of this invention the distributing chamber is made by closing a channel of uniform depth with a wall of varying thickness that causes the cross-section of the chamber to change throughout its length.

Another feature of the invention relates to the construction of tapered distributing chambers by channels of varying depth closed by a wall of uniform thickness.

Other objects, features and advantages of the invention will appear or be pointed out as the specification proceeds.

In the accompanying drawing, forming part hereof:

Fig. 1 is a vertical view, partly in section, of a multi-jet torch embodying this invention.

Figs. 2 and 3 are bottom and end views, respectively, of the torch shown in Fig. 1.

Figs. 4 and 5 are sectional views on the lines 4—4 and 5—5, respectively, of Fig. 1.

Fig. 6 is a vertical view, partly in section, showing a modified form of the invention for use in heating curved surfaces.

Fig. 7 is a fragmentary view showing a portion of the face of the torch of Fig. 6.

Figs. 8 and 9 are sectional views on the lines 8—8 and 9—9, respectively, of Fig. 6.

Fig. 10 is a vertical sectional view through another modified form of the invention.

Fig. 11 is a section on the line 11—11 of Fig. 10.

Figs. 1—5 show a heating tip comprising an elongated block 50 which is made with a channel 51 in its bottom face. Above the channel 51 there is a longitudinal gas passage 52 extending along the entire length of the block 50. The ends of the longitudinal gas passage 52 are closed by plugs 53. A gas inlet opening 55 through the top of the block 50 communicates with the longitudinal passage 52 midway between the ends of the block. There is a connecting passage 56 near each end of the block, between the longitudinal gas passage 52 and the channel 51.

The channel 51 is closed to form a gas distributing chamber 57, by an insert 58 which fits into the channel 51 along the entire length of the channel 51. The insert 58 is highest at its ends where it completely fills the channel 51. These elevated ends of the insert form the end walls 59 of the chamber 57, but it is not essential that these end walls of the chamber 57 be integral parts of the insert 58.

The channel 51 has a shoulder 61 against which a corresponding shoulder on the insert 58 abuts. The insert 58 is held in place by hard solder applied along the lines 62 where the faces of the insert 58 and block 50 come together. The plugs 53 at the ends of the longitudinal gas passage 52 are preferably soldered to the block 50 in the same manner.

With the exception of its end portions 59, the insert 58 does not completely fill any part of the channel 51 above the shoulder 61, and the amount that the insert 58 does extend into that part of the channel above the shoulder 61 varies along the length of the distributing chamber 57. The insert 58 is a wall of varying thickness, along one side of the chamber 57, that gives the chamber different cross-sectional areas at different points along its length.

Jet passages 64 extend through the insert 58. The cross-section of the distributing chamber 51 is greatest at the ends of the chamber adjacent the end jet passages 64. As the chamber 51 extends away from the connecting passages 58 through which gas is supplied to the chamber, its cross-section decreases and reaches a minimum over the jet passages at the middle of the torch. The cross-section of the chamber is preferably proportional to the volume of gas flowing at different regions along its length.

Figs. 6-9 show a modified form of the invention for heating convex curved surfaces, and in the case of the torch illustrated, cylindrical surfaces. The torch includes two block segments 66, each with a channel 67 in its inside face. The channels 67 are of uniform depth, and they are filled by a number of orifice blocks 68, there being three such blocks in the torch shown in Fig. 6, so that the middle block 68 extends across the juncture of the block segments 66, and holds the block segments together.

The parts are connected by hard solder. The orifice blocks are originally made with grooves in their side faces, and when the parts of the torch are first assembled, wires of hard solder 70 are inserted into these grooves and the torch heated sufficiently to fuse the solder and cause it to adhere to the parts.

A narrow channel 71 cut in the middle wall of the channel 67 starts near the lower end of each of the block segments 66 and increases in depth progressively until it reaches its maximum depth at the mid-portion of the torch. When the orifice blocks 68 are in place and connected with the block segments 66, they cover the narrow channels 71 and form with those channels a distributing chamber 73 which progressively decreases in cross-section as it extends away from a central gas inlet passage 74. Gas discharges from the chamber 73 through jet passages 75 in the orifice blocks 68.

Figs. 10 and 11 show a torch tip in which an elongated block 40 has a large central recess closed by a cover plate 42 that has an insert extension 43 on its inside face. The insert extension 43 reaches to the far side of the recess and divides the recess into a longitudinal gas passage 44 and a distributing chamber 45.

The insert extension has a top surface parallel with the top wall of the central recess so that the cross-section of the longitudinal gas passage 44 is uniform throughout the length of the passage 44. The bottom surface of the insert 43 is not parallel with the lower wall of the recess, however, but is angular and slopes toward the center of the lower wall so that the gas distributing chamber 45 is of minimum cross-section near its mid-portion and progressively increases in cross-section toward both ends.

The insert extension 43 is shorter than the recess in the torch block and leaves a clearance 46 at both ends through which gas flows from the passage 44 to the ends of the chamber 45. Gas flows from the chamber 45 through jet passages 47 that open through the bottom face of the tip.

The variation in the cross-sectional area is preferably proportional to the change in the volume of gas flowing at the different regions along the length of the chamber 45.

Several embodiments of the invention have been illustrated and described, but the invention is not limited to these embodiments, and some features of the invention may be used without others.

I claim:

1. In a heating torch comprising an elongated block tip in which is a recess open along a side extending lengthwise of the block, a cover member closing the open side of said recess and forming with said recess a gas distributing chamber, a plurality of jet passages opening into said chamber at spaced points along its length and through which gas from said chamber is discharged through orifices in the face of the tip, and a gas inlet passage opening into the distributing chamber, said cover member having a portion of varying thickness along its length located along a side of the chamber and reducing the open cross-section of the chamber progressively along the length of said chamber as the chamber extends away from the inlet passage.

2. A heating torch comprising an elongated block having a channel in its bottom face, a gas inlet leading into said channel, and walls closing the ends and bottom of said channel to form a distributing chamber, the bottom wall comprising an insert that varies in thickness along its length to reduce the cross-section of the distributing chamber as it extends away from the gas inlet, and flame jet passages opening through the insert.

3. A heating torch including an elongated block with a recess in one side and jet passage extending through the bottom wall of the recess and the bottom face of the block, a gas inlet conduit opening into the top of the recess, a cover plate on the side of the block closing the recess and forming an enclosed space within the torch, and an extension on the inside face of the cover plate dividing the enclosed space into an upper longitudinal gas passage into which said gas inlet conduit opens, and a lower gas distributing chamber into which the jet passages open, said extension terminating short of the ends of the recess to leave the upper passage and lower chamber in communication.

4. A torch for heating curved surfaces, said torch including two arcuate blocks connected together to form a continuous arc, channels in the faces of said blocks, the channel in each block being of increased depth as it approaches the other block, a gas inlet conduit that supplies gas to both channels in the region where the blocks meet, and a plurality of orifice blocks partially filling the channels and forming with said channels gas distributing chambers that decrease in cross-sectional area as they extend away from the inlet conduit.

5. An arcuate heating torch comprising two members including a block with a channel in its bottom face, and an insert fitting within the channel and forming with said channel a distributing chamber, one of said members being of variable cross-section so that the walls of the distributing chamber converge along the length of the chamber, a gas supply conduit communicating with the distributing chamber at the region of maximum cross-section of said chamber, and radially extending jet passages opening through one of said members and into the distributing chamber at spaced points along the arcuate length of said distributing chamber.

6. In an oxy-fuel gas torch in which a plurality of flame jet passages open into a common distributing chamber at spaced points along the length of the distributing chamber, and said chamber is of tapered cross-section with the largest cross-section adjacent a gas supply pas-

sage through which gas enters the chamber, and the cross-sectional area of the chamber at each of the jet passages approximately proportional to the volume of gas flowing at that point, the improvement which comprises a composite block tip including two sections that are connected together and one of which includes a recess that

forms, when covered by the other section, the distributing chamber of the torch, a wall of said recess and a face of the other section that confronts said wall of the recess being out of parallelism so as to obtain the tapered cross-section of said distributing chamber.

HOWARD G. HUGHEY.
